APPARATUS FOR MANUFACTURING
DIAMOND CUTTING TOOLS

Rutherford H. Taylor, Millburn, N. J., assignor
to J. K. Smit & Sons, Inc., New York, N. Y.
a corporation of New York

Application March 29, 1938, Serial No. 198,716

5 Claims. (Cl. 22—65)

This invention is directed to an apparatus which is particularly well adapted for the casting of diamond core bits in which commercial diamonds are set in a metal matrix and function as 5 the cutting medium.

One of the objects of my invention is the provision of an apparatus for casting diamond tools whereby a metal matrix of uniform density and free of gas voids is assured, the diamonds or 10 cutting stones being securely anchored in this matrix and loosening of these cutting stones when the tool is used avoided.

In addition to all of the foregoing, my invention provides for protecting the cutting stones 15 against injury from the molten metal during the operation of casting the matrix or body of the tool.

More specifically the present invention provides a centrifugal casting machine for the casting of core bits and other diamond tools wherein provision is made for enveloping the stones in an inert gas during the casting operation so as to prevent injury to the skin of the cutting stones by the heat of the molten metal. The inert gas 20 is employed not so much as a cooling medium but more by way of a blanket which envelopes the cutting stones during the casting operation to prevent any reaction between the molten metal and the diamond. I have found in casting core 25 bits in accordance with this invention that the cutting stones are unchanged, remaining as bright as the original stones, whereas without the use of the inert gas the stones become blackened and pitted so that their cutting qualities are seriously impaired.

In the accompanying drawings, by way of illustration, I have shown an apparatus which is adapted for the practice of my invention:

Fig. 1 is a longitudinal sectional elevational 40 view of my improved machine;

Fig. 2 is a plan view of the apparatus of Fig. 1; Fig. 3 is a section on the line 3—3 of Fig. 1; Fig. 4 is a section on the line 4—4 of Fig. 1; Fig. 5 is a section on the line 5—5 of Fig. 1; 45 Fig. 6 is a fragmentary view to illustrate the initial stages of the practice of my invention;

Fig. 7 shows in sectional elevation a core bit as it appears when removed from the machine; and

50 Fig. 8 is a similar view of a finished core bit.

Referring to the drawings in detail: 2 designates the turntable of my improved machine and 4 the drive shaft therefor, the turntable being rotated about a vertical axis and being conveniently secured to the drive shaft 4 by a set screw 6.

Mounted on the turntable 2 immediately above the drive shaft 4 is a block 8, secured to the turntable by bolts 10. This block 8 may take any number of forms, but essentially it is provided centrally with a funnel-shaped cavity 12 extending downwardly into the block and then horizontally as shown at 14. Secured in the side of the block 8 by bolts or set screws 15 is a horizontally extending sleeve 16, the bore of which is in line with the horizontally extending portion 14 of the 10 funnel 12.

In line with the sleeve 16 and secured thereto by a split yoke 18 is a removable guide tube 20, the bore of which is in line with the bore of sleeve 16.

The guide tube 20 is for the reception and support of a bit coupling 22. This bit coupling, it will be understood, is preformed, is usually of steel, and it is to this bit coupling that the core bit is to be cast.

As will be seen from Fig. 1, the extremity of the guide tube 20 is slightly reduced in diameter to provide clearance as seen at 23, between the wall of the bit coupling and the tube, the purpose of which will be brought out hereinafter. The guide 25 tube is also shown tapered to the same angle as the bore of the bit coupling. This is merely by way of illustration. The guide tube and the bore of the bit coupling may be straight.

The bit coupling 22 and guide tube 20 extend 30 into the mold cavity 26 of a mold 24. The bit coupling is shouldered at 27 and this shoulder abuts the mold member as shown at 28. Nut 30 clamps the bit coupling to the mold member, so that the bit coupling, the guide tube 20 and the 35 mold 24 are securely clamped or secured to each other.

The mold cavity 26 extend through the outer face of the mold block 24. This outer face of the block is cut back as seen at 31 to provide an annular depression for the reception of a removable die plate 32, which is provided with ports or stone-receiving openings 34. The ports 34 extend through the die plate as will be seen from Fig. 1.

The die plate 32 supports an end plate 36, the 45 adjacent faces of these two plates being depressed to provide a chamber 38 between the two plates, this chamber communicating with a port 40 to which reference will be made in more detail hereinafter.

The die plate 32 and end plate 36 are clamped in position against the end of the mold member 24 by a clamp plate 42. This clamp plate is connected to the lower part of a block 44 which is bolted to the turntable 2, this block 44 being pro- 50 55

vided with a V or cradle 46 which receives and supports the mold member 24 as shown, for example, in Fig. 4.

The bottle of the clamp plate 42 is adjustable toward and away from the block 44 by a bolt 48. In the upper end of the plate 42 I provide a clamp screw 50 which bears against a plug 52 projecting from the outer face of the end plate 36. By proper setting of the bolt 48 and setting up of the screw 50 it will be seen that the end plate 36 and die plate 32 can be securely clamped to each other and to the end of the mold member 24.

As above pointed out, the mold member 24 is supported in the V or cradle 46 in the block 44. It is held in this position by a yoke 54 which is pivoted at 56 and which is provided with clamping screw 58 contacting the mold member 24, all of which is clearly illustrated in Fig. 4.

Again referring to the die plate 32. This plate, as already pointed out, is provided with stone-receiving openings or ports 34 which are regular in shape, round, for instance, and they receive the irregularly shaped cutting stones 60. The disposition of the openings 34 in the die plate 32 depends, of course, upon the desired arrangement of the cutting stones or diamonds in the finished bit.

It will be appreciated, from an inspection of Fig. 1, that when the apparatus is set up the die plate 32 is disposed vertically, and inasmuch as the cutting stones 60 are to be carried on the face of this die plate, it becomes necessary to provide some means for temporarily anchoring the stones in position. To effect this temporary anchorage of the stones in the die plate 32, the same may be sprayed, for example, with any suitable adhesive, as indicated at 62 in Fig. 6, after the cutting stones have been placed in the openings in the die plate, or I may, for example, place a thin layer of powdered wax over the stones and then heat the wax sufficiently to allow it to flow around the stones so as to anchor the stones to the plate.

Inasmuch as the openings 34 in the die plate 32 are of a different shape from the stones which they receive, spaces will be left about the stones 60 between the sides of the stones and the walls of the stone-receiving openings 34. These spaces are not closed by the adhesive 62 and such a construction is deliberately provided in order that an inert gas may be drawn around the sides of the cutting stones and through the openings 34, so that during the casting operation the stones will, in effect, be enveloped in this gas.

This part of my apparatus will now be described. Referring particularly to Figs. 1, 2, 3 and 5, it will be seen that a non-rotatable plate 64 is provided beneath the turntable 2, and to this plate I secure a block 66 by means of bolts 68. The upper face of this block 66 is provided with annular concentric grooves 70 and 72.

Resting upon the block 66 is a similar block 74, the underside of the block 74 being provided with concentric grooves 76 and 78 which register at all times with the grooves 70 and 72, respectively, in the lower block 66. The block 74 is fast to the drive shaft 4 and rotates therewith, the plate 66, as above mentioned, being stationary.

Leading from a suitable suction pump, for example, to the groove or port 70 in the block 66, is a suction line 80, and leading from the groove or port 76 in the upper rotatable block 74 and extending through the turntable 2 is a suction

line 82. This line is connected by a suitable connection such as a flexible metallic hose, for instance, 84, to the port 40 in plug 52 in the outer face of the end plate 36. This port, as above described leads to the chamber 38 between the plate 36 and the die plate 32.

Connected to the annular groove 72 in the fixed plate 66 is a gas line 86 connected to any suitable source of inert gas such as nitrogen. Leading from the complementary groove or port 78 in the rotatable upper block 74 is a gas line 88 which passes up through the turntable 2 and is connected by a suitable connection 90, such as a metallic hose, for instance, to the top of the funnel-shaped filling cavity 12 in the block 8. From an examination of Figs. 1, 2 and 3 it will be seen that a ring 92 is bolted to the top of the block 8, the opening in this ring being in line with the top of the funnel shaped filling opening 12, and that the underside of this ring is provided with an annular groove 94 which communicates with the gas line 90.

Assuming for the moment that suction is drawn on the line 80, it will be apparent that gas will be drawn from the inert gas supply through the line 86, annular ports 72 and 78, gas lines 88 and 90, the annular port 94 in the ring 92 into the filling funnel 12 and from thence through the bores in the sleeve 16 and guide tube 20 to the mold cavity 26, around the cutting stones 60 and through the openings between the sides of the stones and the side walls of the ports 34 in the die 32 and thence to port 40, suction lines 84, 82, annular ports 76 and 70 to the suction line 80.

The blocks 66 and 74 are provided with an oil seal which takes the form of complementary oil grooves 96 in the blocks, these grooves being connected to a source of oil supply 97 through oil conduit 98 connected to each of these grooves by ports 100 with which the block 66 is provided.

In operation, the cutting stones 60 are temporarily anchored in the die plate 32, as above described, and as illustrated in Fig. 6, and then this plate is assembled in the mold as shown in Fig. 1 and clamped in position. The turntable is then rotated about the axis of the drive shaft 4 and suction drawn on the line 80 to draw inert gas through the pouring or charging funnel, etc., about the stones 60 and through the ports 34, as above described, back to the suction device, thereby cleansing the entire mold cavity and enveloping the stones in a blanket of this gas, whereupon with the mold still revolving molten metal is poured into the charging funnel 12 and flows through the tube 20 into the mold cavity 26, and is thrown by centrifugal force against and around the stones 60 so as to embed and securely anchor the stones in the metal. Due to the fact that the mold cavity 26 is considerably larger than the exposed end of the drill coupling 22 there will be considerable movement of metal in the mold cavity which insures that all gas in the mold will be forced out. The major part of this gas will be forced out of the mold through the ports 34.

The drill coupling 22 is provided through its side wall with orifices 102 so that in the casting operation the molten metal will enter these orifices thereby to lock the cast metal to the coupling.

The center of the die plate during the casting operation is provided with a core piece 104 of carbon, for instance. Upon removal of the core bit from the mold the casting is machined down 75

to the form shown in Fig. 8. It will be noticed from Fig. 7, which illustrates the rough casting, that metal filaments or threads 106 project from the working face of the core bit as it is removed from the mold. These threads are the metal which escapes from the mold, during casting, past the cutting stones 60, due to these stones being of a shape other than that of the stone-receiving openings 34.

10 While the construction so far described provides for the escape of gas from the mold during the casting operation, as above pointed out, further means are provided for eliminating gas or allowing the escape thereof which are shown in Fig. 1, for instance. It will be seen upon an inspection of this figure that the mold block 24 is provided with channels or ports 108 which extend from the mold cavity rearwardly through the rear face of the block 24. In the casting operation, therefore, any gas which does not escape past the cutting stones can and will be forced out of these leak ports 108 to the outside of the mold. The ports are closed by a washer 110, asbestos for instance, which prevents any substantial escape of metal but will permit of the escape of gas, as will be understood.

It is to be understood that changes may be made in the details of construction and arrangement of parts hereinabove described without departing from the spirit and scope of my invention.

What I claim is:

1. Molding apparatus comprising in combination a mold, means for revolving the same about a vertical axis, a die plate for supporting cutting stones in the mold in a vertical plane lying outside the axis of revolution of the mold, and suction means for drawing inert gas about said stones while pouring molten metal into the mold.

40 2. Molding apparatus comprising in combination a horizontally disposed mold, a die plate across the end of the mold cavity and supporting cutting stones in a vertical plane, means for revolving the mold about a vertical axis lying outside the plane of the cutting stones, and suction means for drawing an inert gas about the cutting stones while the mold is being revolved and molten metal is being charged thereto.

3. Molding apparatus comprising in combination a mold, a channelled rotary block, means for revolving said mold and rotating said block simultaneously, a stationary channelled block co-operating with the said rotary block, suction means and an inert gas supply connected to the channels of said stationary block, a suction line connected to the rotary block and communicating with the cavity of said mold, and a gas line leading from the said rotary block to another part of the mold cavity, whereby as the mold is revolved inert gas from said supply is drawn through the mold cavity.

5 tion a mold, a channelled rotary block, means for revolving said mold and rotating said block simultaneously, a stationary channelled block co-operating with the said rotary block, suction means and an inert gas supply connected to the channels of said stationary block, a suction line connected to the rotary block and communicating with the cavity of said mold, and a gas line leading from the said rotary block to another part of the mold cavity, whereby as the mold is revolved inert gas from said supply is drawn through the mold cavity.

4. Molding apparatus comprising in combination a mold, a turntable supporting the same, means for rotating the turntable to revolve the mold, a block on said turntable having a filling opening concentric with the axis of rotation of the turntable and communicating with the cavity of said mold, a gas connection communicating with said filling opening, a suction line communicating with said mold cavity, a stationary gas supply, a stationary suction means, and rotatable means for maintaining constant communication between the gas supply and suction means, whereby as the mold is revolved gas is drawn through the filling opening of the mold and through the mold cavity to the suction means.

5. Molding apparatus comprising in combination a turntable, a mold mounted thereon, its cavity lying outside the axis of rotation of the turntable, a drive shaft attached to said turntable for rotating the same, a channelled block attached to said drive shaft and rotated therewith, a gas line leading from said block to the filling opening of the mold, a suction line leading from said block to the mold cavity, said gas line and suction line revolving with the turntable, a fixed block having channels in constant communication with the channels in the rotatable block, a gas supply connected permanently to one of the channels in the fixed block, and suction means connected permanently to the other channel in the fixed block, whereby gas can be drawn into the filling opening of the mold 40 and through the mold cavity as the mold is revolving.

RUTHERFORD H. TAYLOR.
